UNITED STATES PATENT OFFICE.

BRUCE FORD, OF PHILADELPHIA, PENNSYLVANIA.

STORAGE BATTERY.

1,271,148.

Specification of Letters Patent.

Patented July 2, 1918.

Application filed May 21, 1917. Serial No. 169,896.

To all whom it may concern:

Be it known that I, BRUCE FORD, a citizen of the United States, residing at Philadelphia, in the county of Philadelphia and State of Pennsylvania, have invented certain new and useful Improvements in Storage Batteries, of which the following is a specification.

The cells of some storage batteries, more especially the storage batteries of submarine and other boats, do not contact with each other and space, utilized for wedges, is left between their walls. This space is desirable for purposes of ventilation, drainage and cooling, but is undesirable because extraneous objects are likely to fall into it, and the arrangement of the cells with space between them is not well suited to afford men an opportunity to walk on top of the cells as they sometimes wish to do for purposes of inspection and repairs.

It is the object of the present invention to provide a combing which will cover the space referred to, which can be easily applied, which will not interfere with proper drainage, cooling and ventilation, and which affords a good foot-hold for men to walk on.

The invention will be claimed at the end hereof but will be first described in connection with the embodiment of it chosen for illustration in the accompanying drawing in which—

Figure 1, is a top or plan view of a portion of a battery provided between its cells with a combing embodying features of the invention.

Fig. 2, is a side view, partly in section, of the same.

Fig. 3, is a sectional view, drawn to an enlarged scale, of the combing and showing a portion of the cells to which it is applied.

Fig. 4, is a side view of the combing, and

Fig. 5, is a plan view of the under side of the combing.

The combing consists of a head 1, provided with a web 2, and it has a series of spaced notches 3, extending in the direction of the web and underneath the head. The ends of the sections of combing may be cut away, as at 4, for the accommodation of sections of 50 combing crossing each other at right angles. The combing is made of soft rubber and is flexible, and one advantage of this is that the combing pieces can be installed underneath the ventilating ducts 5, and copper 55 connectors 6, by bending and curling them around and underneath these obstructions. Again, being of soft rubber, these combing pieces adjust themselves to the making of a good fit, and they afford a nice finish and 60 make a good foot-path for men to walk on over the tops of the cells. The notches 3, provide drainage to the bottom of the battery compartment for any water or spilled electrolyte, which might otherwise lie on top of the cells, and the notches also provide for air circulation which tends to cool the battery.

Changes may be made in details since the invention is not limited as to those matters or otherwise than as the prior art and appended claims may require.

I claim:

1. A combing piece for storage batteries consisting of a strip of soft flexible rubber 75 and having a head and a web.

2. A combing piece for storage batteries provided with a head and a web and having a series of spaced notches extending in the direction of the web and underneath the 80 head and having open ends affording drainage.

BRUCE FORD.
